CLAIM

The ornamental design for a wireless transmitter, as shown and described.

DESCRIPTION

FIG. 1 is a perspective view of a wireless transmitter showing my new design;

FIG. 2 is another perspective view;

FIG. 3 is a front view;

FIG. 4 is a rear view;

FIG. 5 is a left side view;

FIG. 6 is a right side view;

FIG. 7 is a top view; and,

FIG. 8 is a bottom view.

The broken lines showing portions of the wireless transmitter represent portions of the design that are not claimed and form no part of the claimed design.
